ATTY.

UNITED STATES PATENT OFFICE.

LOUIS M. SCHMIDT, OF LYNN, MASSACHUSETTS, ASSIGNOR TO GENERAL ELECTRIC COMPANY, A CORPORATION OF NEW YORK.

CURRENT-TRANSFORMER.

1,022,880.

Specification of Letters Patent.

Patented Apr. 9, 1912.

Application filed September 11, 1908. Serial No. 452,576.

To all whom it may concern:

Be it known that I, Louis M. Schmidt, a citizen of the United States, residing at Lynn, county of Essex, State of Massachusetts, have invented certain new and useful Improvements in Current-Transformers, of which the following is a specification.

This invention relates to apparatus for transforming electric currents by induction between two interlinked conductors, and has especial reference to what are called "current" transformers for producing currents of small volume for use in meters and other instruments on the switchboards of power stations. It is customary to build such transformers for primary currents of a given value, the secondary being wound to give a current having a certain predetermined ratio thereto, and the instruments being calibrated for this ratio. But it may sometimes happen that the station attendant will wish to use such a transformer with a primary current of much greater or less value. In this event, he must make proper allowance in reading his instruments—a matter which may lead to mistakes and possible damage.

The object of my invention is to provide a current transformer in which the primary can be so connected as to give one ratio with heavy currents and another ratio with lower currents; in such fashion that the instruments may be read directly in either case.

A further object is to provide a strong and compact construction dispensing with wires in the primary winding, and utilizing said primary as a support for the secondary coil and the connecting rod and links hereinafter described.

To these ends, the invention consists in a current transformer having its primary winding composed of a stout bar divided longitudinally into preferably two sections, suitably insulated from each other, with means for connecting said sections in series or in parallel, at will. On this bar is mounted the secondary coil, and to its ends are attached not only the line terminals or bus bars, but also the links or blocks which support the connecting rod used to connect the sections in series.

The specific features of novelty will appear from the following detailed description and claims, taken in connection with the accompanying drawing, in which—

Figure 1 is a perspective view of a current transformer embodying my invention, Fig. 2 is a diagram showing the transformer with the two sections of the primary connected in series, Fig. 3 is a diagram showing said sections connected in multiple, Fig. 4 is an end view of the arrangement shown in Fig. 1 and Fig. 5 is an end view showing the sections of the primary connected in multiple.

The secondary coil is shown at 1, concentric with the primary winding, which consists preferably of two parallel lengths or sections 2 3 insulated from each other. A convenient mode of construction is that shown in Figs. 1 and 4, where two semi-cylindrical bars are laid on each side of a strip 4 of insulation, thus forming a stout bar divided longitudinally into sections suitably insulated from each other. At opposite ends of said bars there are wide flattened portions 5 5' forming line terminals. The other ends of the bars are preferably flattened also, to facilitate the attachment thereto of links 6 6' by means of which the bars may be connected to a rod 7 running parallel with the bars outside of the coil 1. Spacers 8 of insulating material connect said rod with the terminals 5 5'.

When connected as shown in Figs. 1, 2 and 4, the two bars are in series, the circuit being from line to the terminal 5, and thence by way of the bar 2 and link 6 to the rod 7, link 6', bar 3 and terminal 5' to line.

In Figs. 3 and 5, the rod 7, links 6, 6' and spacers 8 are omitted, and a U-shaped clip 9 is secured over each end of the sectional primary, thus connecting the two bars 2 3 in parallel.

The construction can be modified to a considerable extent without departing from the spirit or scope of my invention.

What I claim as new and desire to secure by Letters Patent of the United States, is,

1. A current transformer having a primary winding composed of a stout bar divided longitudinally into sections with insulation between the sections, a connecting rod parallel with said bar, links for connecting said bar sections and rod in series, and a secondary winding in inductive relation with said primary winding.

2. A current transformer having a primary winding consisting of a stout bar divided longitudinally into sections with in-

sulation between them, a secondary coil supported on said bar, and devices connecting said bar sections and also supported thereby.

3. A current transformer having a primary winding consisting of a stout bar divided longitudinally into sections with insulation between them, a secondary coil supported on said bar, a connecting rod parallel

with said bar, and links for connecting said sections and rod in series.

In witness whereof I have hereunto set my hand this fifth day of September, 1908.

LOUIS M. SCHMIDT.
